(57) **CLAIM**

The ornamental design for lacrosse head, as shown and described.

DESCRIPTION

FIG. 1 is a front view of the lacrosse head embodying the new design;

FIG. 2 is a rear view thereof;

FIG. 3 is an enlarged view of the left side of the lacrosse head of FIG. 1, the right side of the lacrosse head as shown in FIG. 1 being a mirror image thereof; and,

FIG. 4 is an enlarged view of the left side of the lacrosse head of FIG. 2, the right side of the lacrosse head as shown in FIG. 2 being a mirror image thereof.

FIGS. 1–4 show features of a lacrosse head in phantom lines. These features are shown for environmental purposes and do not form any part of the claimed design. The claimed features of the lacrosse head in solid lines represent the outermost boundary of the lacrosse head in the solid line locations when the lacrosse head is viewed from the perspectives of FIGS. 1–4.
